UNITED STATES PATENT OFFICE.

JULES D. BISCAYART AND FERNAND CAILLETEAU, OF ATLANTA, GEORGIA.

MEANS FOR OPERATING ELECTRIC-LAMP SWITCH-BUTTONS.

1,264,763.

Specification of Letters Patent. Patented Apr. 30, 1918.

Application filed September 5, 1917. Serial No. 189,880.

To all whom it may concern:

Be it known that JULES D. BISCAYART and FERNAND CAILLETEAU, citizens of the United States, residing at Atlanta, in the county of Fulton and State of Georgia, have invented certain new and useful Improvements in Means for Operating Electric-Lamp Switch-Buttons; and they do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in attachments to snap switches and consists in the provision of a simple and efficient device of this nature, adapted to be held by resilient fingers upon a bulb socket and having a spring pressed slotted oscillating member for the reception of the button of the switch and a single cord attachment for turning the member in one direction.

Our invention consists of a simple and efficient device of this nature having various details of construction, combinations and arrangements of parts which will be herein-after fully described, shown in the accompanying drawings and then specifically defined in the appended claims.

We illustrate our invention in the accompanying drawings, which with the letters of reference thereon form a part of this application and in which:

Figure 1 is an edge view in elevation showing the application of the invention to a bulb socket.

Fig. 2 is a front elevation.

Fig. 3 is a sectional view on line 3—3 of Fig. 2.

Fig. 4 is a view in elevation with the outer shell removed, and

Fig. 5 is a perspective detail view of the pawl pin.

Reference now being had to the details of the drawings by letter:

50 A designates a ring having two resilient fingers A' projecting therefrom at points diametrically opposite and forming means for attachment to the bulb socket. Said ring has slots B formed therein at the base 55 of said fingers and adapted to receive the lugs C of the housing D having a central

opening D' therein and which with the ring form inclosures for the operative parts of the device. A cylindrical slotted shell E has two shoulders F and H, the former of which has a bearing in the circular outlined opening of the ring, and said shoulder H a bearing in the circular outlined opening in said housing. Said shell has a series of circumferential perforations J formed therein and is provided with intersecting slots K for the reception of the button of a switch.

A circumferentially grooved ring, designated by letter L, is journaled about the perforated portion of said shell and has oppositely disposed lugs N struck up therefrom carrying the pivotal pin O upon which a pawl P is pivotally mounted and the pawl has a hooked end passing through the slot R in said circumferentially grooved ring and which pawl is adapted to engage the perforations of the shell when the ring carrying the pawl is moved in one direction, thus causing the shell to rotate with the ring. A lug T is struck up from the inner face of the ring A and one end of a coiled spring is attached to said lug T and its other end is attached to a struck up lug R in the wall of the groove of the ring. The purpose of said spring is to normally return the pawl carrying ring to its normal position after having been rotated by a cord or chain S which is fastened to the circumference of the ring, and which is guided in the groove of the ring and passes through a slot X in the housing.

In operation, the spring fingers are caught over the socket of the bulb, the key to a switch passing through one of the intersecting slots. When the device is thus securely held upon the socket, by pulling upon the cord the grooved ring to which the same is attached may be given a partial rotary movement and the pawl carried by the ring engaging the perforated shell will cause the latter to rotate and return the switch button against the tension of the coiled spring. When the cord is released the spring will return the ring to its starting position, the pawl turning idly over the circumference of the shell.

105 What we claim to be new is:

1. A device for operating buttons of snap switches comprising a ring and means for attaching the same to a bulb socket, an oscillating cylindrical shell journaled in said ring and having a slot for the reception of a switch, a grooved ring journaled upon said

shell, a cord attached to and adapted to be guided in said groove, a pawl pivotally mounted upon the grooved ring and having its free end passing through a slot therein, the circumference of the shell being perforated to receive the pawl, a spring attached to one end of the grooved ring and its other end to the stationary ring.

2. A device for operating buttons of snap switches comprising a ring and means for attaching the same to a bulb socket, an oscillating cylindrical shell journaled in said ring and having a slot for the reception of a switch, a grooved ring journaled upon said shell, a cord attached to and adapted to be guided in said groove, a pawl pivotally mounted upon the grooved ring and having its free end passing through a slot therein, the circumference of the shell being perforated to receive the pawl, said rings each having a struck up lug, and a spring attached to said lugs adapted to return the shell to its starting position.

3. A device for operating buttons of snap switches comprising a ring having resilient fingers for engagement with a bulb socket and provided with slots, a housing having lugs engaging said slots, a cylindrical shell having shouldered portions journaled in the openings of said ring and housing and having a series of circumferential perforations, a grooved ring journaled about said shell and having a slot therein and lugs struck up from the opposite edges, a pawl pivoted upon said lugs with its free end passing through the slot in the ring and adapted to engage the perforations of the shell to said rings, a cord fastened to the grooved ring, and a housing about the grooved ring.

In testimony whereof we hereunto affix our signatures in presence of two witnesses.

JULES BISCAYART.
FERNAND CAILLETEAU.
